INSERT UNIT FOR CONVERTING A REFRIGERATOR TO A COMBINED REFRIGERATOR AND FREEZER

Delbert R. Reedy, Los Angeles, Calif., assignor to Kardel Products Corporation, Los Angeles, Calif.

Filed July 1, 1971, Ser. No. 159,096

Term of patent 14 years

Int. Cl. D15—07

U.S. Cl. D67—3 R

FIG. 1

FIG. 2

FIG. 3

FIG. 4

FIG. 1 is a front elevational view of an insert unit for converting a refrigerator to a combined refrigerator and freezer showing my new design;

FIG. 2 is a top plan view thereof;

FIG. 3 is a bottom view thereof; and

FIG. 4 is a right side elevational view thereof, the left side being a mirror image of the right;

The rear of the insert unit is flat and unornamented.

I claim:

The ornamental design for an insert unit for converting a refrigerator to a combined refrigerator and freezer, substantially as shown and described.
